UNITED STATES PATENT OFFICE.

JOSEPH H. HEDMARK, OF CHICAGO, ILLINOIS.

FURNACE.

1,412,178.

Specification of Letters Patent. Patented Apr. 11, 1922.

Application filed December 17, 1917. Serial No. 207,523.

To all whom it may concern:

Be it known that I, JOSEPH H. HEDMARK, a citizen of the United States, residing at Chicago, in the county of Cook and State 5 of Illinois, have invented certain new and useful Improvements in Furnaces, of which the following is a specification.

This invention relates to furnaces which may be used for various purposes, but are 10 particularly adapted for heating buildings or the like where it is desirable to operate the same with comparatively little attention, and yet maintain a uniform heat.

The objects of this invention are to improve the general construction of furnaces; to provide an improved form of furnace which will burn various grades of coal with practically perfect combustion; to provide an improved furnace in which all of the 20 gases generated will be carried to a combustion chamber where their oxidation will be complete; to provide a furnace in which all the air will ordinarily be admitted above the fuel, and which will have passage-ways 25 or flues arranged to balance or compensate the draft through the fuel and to the combustion chamber; and in general to provide such an improved construction as will be described more fully hereinafter.

30 In the accompanying drawings illustrating this invention,

Fig. 1 is a longitudinal, sectional view showing my improved furnace as arranged for a vertical tubular boiler; and,

35 Fig. 2 is a front view of the same, parts being broken away to show the interior construction.

One of the principal features of this invention consists in the arrangement whereby 40 air is admitted into a space above the fuel, and one or more flues are provided for carrying the air and gases from this space to a chamber below the grates, and flues or passages are also preferably provided 45 whereby some of the air and gases may pass directly from the space above the fuel to the combustion chamber. In the particular form of furnace shown in these drawings, 3 represents the fuel chamber or the main 50 portion of the furnace which is provided with grates 4 of any desired form of construction at some distance above the bottom thereof. The fuel is inserted through the doors 5 and 6, the former being used for 55 starting the fire, and also for raking the grates or stirring up the coal. The chamber

3 extends for some distance above the door 6, and one or more flues or passage-ways 7 lead from the top of this chamber to the portion 8 thereof below the grates 4. In 60 the arrangement shown, this flue is built in the side wall 9, but it may be otherwise arranged if desired. The space 8 is provided

with a door 10 for cleaning out the ashes, and for admitting air when desired. The 65 back wall 11 of the furnace has a relatively narrow opening or passage-way 12 which leads from the chamber 3 to a combustion chamber 13 formed under the boiler 14. A wall 15 extends across underneath the boiler 70

14, so that the gases of combustion pass up through the tubes 16 in one side of the boiler to a chamber 17 at the top of the boiler, then down through the tubes 18, to a second chamber 19, from which they pass 75 out through the flue 20 formed in the brick work 21, and from there to a pipe or stack 22. The furnace is provided with an air inlet 23 at a short distance from the top of the chamber 3, this inlet being provided 80 with a draft door 24 for regulating the amount of air admitted. A check draft 25 is also provided which opens into the chamber 19, this draft being provided with a door 26. The doors 24 and 26 may be connected 85 so as to be operated by automatic means in any well known manner, if desired. The boiler 14 is intended to represent any suitable form of heat generating or distributing apparatus, as it is apparent that 90 my improved furnace may be utilized for heating a steam or hot water boiler, or hot air drum, or the like.

When a fire is first kindled or started in the furnace, the door 24 may be closed, and the door 10 opened, so as to give a direct draft through the grates. When the fire is well started, the coal or fuel may be gradually added until it reaches the position shown approximately by dotted lines in Fig. 1. 100 The door 10 is then closed, and all of the air necessary for combustion is admitted through the door 24 and the main portion of this air will go down through the coal to give a down draft to the passageway 12. Part of the gases generated from the coal 105 will pass with the products of combustion through the opening 12 to the combustion chamber 13, where the combustion is further completed. Another portion of the gas 110 generated from the coal or fuel will pass up into the upper portion of the chamber

3, and be mixed with the air entering through the inlet 23. A portion of this mixed air and gas will pass down through the flue 7 underneath the grates 4, and the 5 gas will there be ignited, and will assist in the combustion of the coal. If the chamber 3 is filled so that the top of the coal or fuel reaches a point above the opening 12, it is prevented from entering the opening 10 by a cross wall or partition 27. This partition extends across the back of the chamber 3, and is spaced from the wall 11 so as to leave a flue or passage-way 28. Under these circumstances, a portion of the 15 mixed air and gases may pass down through the flue 28 to the opening 12, and from thence to the combustion chamber 13, where the gas is consumed and the air further assists in the combustion of the gases coming 20 directly from the coal through the opening 12. It will be understood, of course, that the combustion is continued as the gases pass up and down through the tubes of the boiler. It will be seen from this 25 description that I provide a furnace in which the main down draft is equalized by an up draft through the grates so that there is always a sufficient amount of air furnished to complete the combustion even if the coal 30 becomes packed or there is a stoppage of the draft in either direction and the draft is not apt to be sufficiently violent to carry away the unburned gases. I have found in actual use, that even very poor grades of 35 soft coal may be burned in this furnace with practically no visible smoke after the fire is well started. Furthermore, by adjusting the inlet door 24 and check draft 26, the fire may be kept burning at a uniform rate 40 for many hours without giving the furnace any attention. The adaptability of this furnace for burning low grade fuel, constitutes one of its particular advantages.

It will be noted that changes in the arrangement of parts and details of construction may be desired to adapt the furnace for different conditions, or for heating different types of boilers, or hot air heaters, and therefore, I do not wish to limit myself to the exact construction or arrangement herein described.

What I claim as my invention and desire to secure by Letters Patent is:

1. A furnace comprising a closed chamber having grates arranged at some distance above the bottom thereof, said chamber having an outlet at a short distance above the grates, a combustion chamber connected with said outlet, a passage-way

from the upper portion of said chamber 60 leading to the lower portion thereof below the grates, said first named chamber having an air inlet at the upper portion thereof, and one or more doors for putting fuel into said chamber. 65

2. A furnace having a fuel chamber with grates at some distance above the bottom thereof, and having an outlet at a short distance above said grates, a flue leading 70 from the top of the chamber to a point below the grates; a flue leading from the top of the chamber to said outlet, said chamber having an air inlet arranged above the fuel line.

3. In an apparatus of the character set 75 forth, the combination of a fuel chamber, grates arranged above the bottom of said chamber, a combustion chamber arranged adjacent to said fuel chamber, a passage-way connecting said chambers, and arranged 80 a short distance above said grates, a cross wall in the back of the fuel chamber to prevent the fuel from entering said passage-way, and also providing a flue from the top of the chamber to said passage-way, a door 85 for inserting fuel into the fuel chamber, and said fuel chamber having an air inlet above the fuel line.

4. In an apparatus of the character set 90 forth, the combination of a fuel chamber, grates adjacent to the bottom of said chamber for supporting the fuel, a combustion chamber adjacent to said fuel chamber, a boiler, located in said combustion chamber, a passage-way leading from said fuel 95 chamber to the combustion chamber below said boiler, a cross wall in said fuel chamber spaced from the wall through which said passage-way extends, said cross wall extending from said passage-way to a point adjacent to the top of the chamber, a flue leading from the top of the chamber to a point below the grates, an air inlet draft above the fuel line of the fuel chamber, a check draft, and doors opening into said chamber 105 above and below the grates for inserting fuel and removing the ashes.

5. A furnace comprising a fuel chamber, having grates at some distance above the bottom thereof, said fuel chamber having 110 an air inlet above the fuel line, and having a passageway leading from above the fuel line to a chamber below the grates, and another passageway leading from above the fuel line back of the grates to a combustion chamber, substantially as described. 115
